US00D978088S

(12) **United States Design Patent** (10) Patent No.: **US D978,088 S**
(45) Date of Patent: ** *Feb. 14, 2023

(54) **CONTROL DEVICE**

- (71) Applicant: **Lutron Technology Company LLC**,
Coopersburg, PA (US)
- (72) Inventors: **Brad Michael Kreschollek**, Bethlehem,
PA (US); **Noel Mayo**, Philadelphia, PA
(US); **Nayda Aponte**, Northampton, PA
(US)
- (73) Assignee: **Lutron Technology Company LLC**,
Coopersburg, PA (US)
- (*) Notice: This patent is subject to a terminal disclaimer.
- (**) Term: **15 Years**
- (21) Appl. No.: **29/825,427**
- (22) Filed: **Feb. 1, 2022**
